UNITED STATES PATENT OFFICE.

PAUL L. GEER, OF BELLEVUE BOROUGH, PENNSYLVANIA, ASSIGNOR TO AMSLER-MORTON COMPANY, OF PITTSBURGH, PENNSYLVANIA, A CORPORATION OF PENNSYLVANIA.

MUFFLE-LEER CONSTRUCTION.

1,385,868.

Specification of Letters Patent. Patented July 26, 1921.

Application filed November 25, 1919, Serial No. 340,468. Renewed October 7, 1920. Serial No. 415,376.

To all whom it may concern:

Be it known that I, PAUL L. GEER, a citizen of the United States, and residing in the borough of Bellevue, in the county of

5 Allegheny and State of Pennsylvania, have invented or discovered new and useful Improvements in Muffle-Leer Construction, of which the following is a specification.

10 My invention consists of new and useful improvements in muffle leers.

The objects which I have in view are, *inter alia*, as follows:

To provide a leer in which the gaseous products of combustion are brought into 15 such intimate contact with the walls of the muffle that the maximum heating effect is obtained.

To provide the proper temperature gradient from the front to the rear of the leer.

20 To provide a gas tight muffle of improved construction which will allow for the necessary expansion and contraction without leakage or rupture.

To provide an inexpensive, yet efficient, 25 durable and easily repaired muffle leer.

For these and other objects, I have invented a muffle leer in which the combustion of the gaseous fuel takes place under the forward end of the muffle, the products 30 of combustion being led upwardly through vertical flues at the sides of the muffle to the crown, and thence downwardly through reverse flues to a chamber in the rear of and separated from the combustion chamber.

35 Thence the products are led up through flues at the sides of the muffle to the rear portion of the crown which is separated from the forward portion of the crown by a baffle or intersecting wall, and thence said 40 products pass along the crown extension to

the stack in the rear of which is the tunnel which extends to the discharge door of the leer. The third or rear series of vertical flues are preferably of less capacity or fewer 45

in number than the first and second named series to prevent too rapid passage of the products of combustion. The travel of the products of combustion is further regulated by the stack damper, while the intensity of 50 the heat in the combustion chamber is regulated by the air and gas valves of the burner, where a gas burner is used.

The outer walls and roof of the leer may be of the usual fire brick construction, but

I provide for the structure of the muffle, the 55 flues and the crown extension special interlocking tiles whose joints are rendered gas-tight by means of plastic cement.

In the rear of the muffle the side walls of the leer are contracted inwardly into alignment with the walls of the muffle, and the leer walls are provided with projecting abutment tiles for supporting the inner roof arch to form the crown extension at the rear end of which is the stack. In the rear of the 65 stack is the usual prolonged tunnel whose walls and roof are of fire brick and are aligned with the walls and roof of the muffle.

In the accompanying drawings, which are merely intended to illustrate the principles 70 of my invention without limiting the scope of the same to the construction shown, Figure 1 is a central longitudinal section of the muffle portion of a leer embodying my present improvements taken along the line I—I 75 in Fig. 2; Fig. 2 is a section of the same taken along the line II—II in Fig. 1; Fig. 3 is a horizontal section taken along the irregular line III—III in Fig. 2; Fig. 4 is a broken central longitudinal section of the 80 complete leer; Fig. 5 is a section taken along the line V—V in Fig. 4, showing the crown extension construction; Fig. 6 is a similar view taken along the line VI—VI in Fig. 4, showing the tunnel construction; Fig. 7 is an enlarged section taken along the 85 line VII—VII in Fig. 2 showing the muffle arch or roof construction; Fig. 8 is an enlarged perspective of one of the muffle wall tiles, and Fig. 9 is a similar view of one of 90 the muffle floor tiles.

The following is a detailed description of the embodiment of my invention shown in the drawings.

The outer structure of the leer is preferably constructed of the usual fire brick supported by buckstays, not shown. It is composed of a forward portion A within which is the muffle; the crown extension portion B, and the tunnel portion C. 1 is the 95 foundation or base; 2 the side walls, and 3 the top arch or roof. The muffle portion of the leer is of greater depth, as shown to provide for the combustion chamber 4 under the forward portion of the muffle D and the reverberatory chamber 5 under the rear portion of the muffle and separated from the combustion chamber by the back wall 6.

The gas burner E extends through the front wall of the combustion chamber and is provided with a gas valve 7 and an air valve 8.

The muffle D is supported by the wing walls 9 extending inwardly from the side walls 2 of the leer and vertical piers 10.

The side walls of the muffle D are formed by vertically disposed wall tiles 11 having inner and preferably paneled faces 12 and 10 rearwardly extending vertical edge flanges 13 which when the tiles 11 are assembled on the wing walls 9, as shown in the drawings, to form the walls of the muffle, extend outwardly into contact with the walls 2 of the 15 leer. The tiles 11 span the spaces between the wing walls 9, and thus the flanges 13 form with said wing walls vertical flues 14 in the sides of the muffle. The floor of the muffle is composed of floor tiles 15, tongued 20 and grooved at their edges to interlock, the edges of the outside tiles interlocking with an undercut portion of the tiles 11, as shown in Fig. 2. The floor tiles are supported on the wing walls 9 and piers 10.

25 The roof arch of the muffle is composed of arch tiles 16, and roof tiles 17 supported by the former.

The arch tiles are provided with tongues and grooves on their ends so that they form 30 spaced apart arches supported at their ends by the tongue and grooved abutments of the wall tile 11. Said arch tiles 16 are provided on their sides with trough flanges 18. The roof tiles 17 are tongued and grooved together, at their ends and their longitudinal 35 edges are provided with depending lips or flanges 19 which fit into the flanges 18, and so support the roof tiles in place.

The joints between the tiles are filled with 40 a plastic cement 20 to make an expandible but gas-tight union. For this purpose, I prefer to use a mixture of 25% of silicate of soda and 75% of low grade fire clay, thus obtaining a cement which fuses at about 1600 45 Fahr.

The front of the leer and of the muffle is closed by the front wall 21 through which the burner E extends into the combustion chamber 4. A door or doors 22 closes the 50 front of muffle D, while 23 is a peep or cleaning hole leading into the front end of the crown flue and normally closed with a suitable closure.

24 is a vertical baffle intersecting the crown 55 flue at a point above the chamber 5.

At the rear of the muffle D, the walls 2 of the leer contract into line with the side walls of the muffle and are provided with 60 inwardly projecting abutment tile 25 having inclined tongued and grooved faces which support the roof arches for the crown extension. In the rear of the crown extension B the roof of the leer is lowered to form the tunnel C whose side walls and roof 65 are substantially aligned with the side walls

and roof of the muffle. The stack F is mounted on the leer at the rear end of the crown extension.

It is evident that the first series of vertical flues 14, in front of the back wall 6, 70 are up flues; that the next series of flues 14 in front of the baffle 24 are down flues, and the flues 14 in the rear of the baffle 24 are up flues.

Thus the products of combustion travel 75 upwardly from the combustion chamber around the muffle, thence back along the crown flue and thence down around the muffle into the chamber 5 and thence up around the muffle to the crown flue and 80 thence rearwardly along the extension of the crown to the stack.

It is thus evident that the entire length of the muffle is completely enveloped by the products of combustion, the heat gradually 85 lessening from the front to the rear, and the intensity of the heat and the travel of the products of combustion being adjustable with nicety by means of the burner valves and stack damper.

90 My leer is much simpler, and less expensive in construction than the types of muffle leer now in use. My leer is not damaged by expansion and contraction due to temperature changes, nor will such changes result in the 95 entrance of sulfur or other injurious fumes into the interior of the muffle. The tile construction is so designed as to be of remarkable strength and durability, and quick and easy repairs are made by the substitution of 100 new tiles when necessary.

Although, for the sake of clearness of illustration of the principles of my invention, I have minutely described the embodiment of the same shown in the accompanying drawings, I do not wish to limit myself thereby, but claim broadly:—

1. A muffle leer comprising an outer furnace structure, an elevated muffle mounted therein, a longitudinal crown flue above the 110 muffle, a combustion chamber under the forward portion of the muffle, a reverberatory chamber under the rear portion of the muffle, a vertical wall separating said chambers, a baffle wall intersecting the crown flue above 115 the reverberatory chamber, a series of vertical flues on either side of the muffle connecting the combustion chamber with the crown flue; a second series of vertical flues at either side of the muffle, and in rear of said first 120 named flues, connecting the crown flue in front of the baffle wall with the reverberatory chamber, a third series of vertical flues, in the rear of said second named flues, connecting the reverberatory chamber with 125 the crown flue in the rear of the baffle wall, and means for leading off the products of combustion from the rear end of the crown flue, whereby the products of combustion 130 ascend from said combustion chamber about

said muffle to the crown flue, thence descend from said crown flue about said muffle to said reverberatory chamber, and thence ascend from said reverberatory chamber about said

5 muffle to the crown flue in the rear of said baffle wall.

2. A muffle leer comprising an outer furnace structure, an elevated muffle mounted therein, a longitudinal crown flue above the muffle, a combustion chamber under the forward portion of the muffle, a reverberatory chamber under the rear portion of the muffle, a vertical wall separating said chambers, a baffle wall intersecting the crown flue above the reverberatory chamber, a series of vertical flues on either side of the muffle connecting the combustion chamber with the crown flue; a second series of vertical flues at either side of the muffle, and in rear of said first named flues, connecting the crown flue in front of the baffle wall with the reverberatory chamber, a third series of vertical flues, in the rear of said second named flues, connecting the reverberatory chamber with the crown flue in the rear of the baffle wall, said third named flues having a combined capacity less than that of the second named flues, and means for leading off the products of combustion from the rear end of the crown flue, whereby the products of combustion ascend from said combustion chamber about said muffle to the crown flue, thence descend from said crown flue about said muffle to said reverberatory chamber, and thence ascend from said reverberatory chamber about said muffle to the crown flue in the rear of said baffle wall.

3. A muffle leer comprising an outer furnace structure, an elevated muffle mounted therein, a longitudinal crown flue above the muffle, the side walls of the outer furnace being contracted in the rear of the muffle into alinement with the side walls of the latter to form a tunnel and the crown flue being extended beyond the rear end of the muffle, a combustion chamber under the forward portion of the muffle, a reverberatory chamber under the rear portion of the muffle, a vertical wall separating said chambers, a baffle wall intersecting the crown flue above the reverberatory chamber, a series of vertical flues on either side of the muffle connecting the combustion chamber with the crown flue; a second series of vertical flues on either side of said muffle, and in the rear of said first named flues, connecting the crown flue with the reverberatory chamber, and a third series of vertical flues on either side of said muffle, and in the rear of said second named flues, connecting the reverberatory chamber with the crown flue in the rear of the baffle wall, whereby the products of combustion ascend from the combustion chamber to the crown flue, thence descend from the crown flue to the

reverberatory chamber, and thence ascend from the reverberatory chamber to the crown flue in the rear of said baffle to escape to atmosphere.

4. A muffle leer comprising an outer furnace structure, an elevated muffle mounted therein, a longitudinal crown flue above the muffle, the side walls of the outer furnace being contracted in the rear of the muffle into alinement with the side walls of the latter to form a tunnel and the crown flue being extended beyond the rear end of the muffle, a combustion chamber under the forward portion of the muffle, a reverberatory chamber under the rear portion of the muffle, a vertical wall separating said chambers, a baffle wall intersecting the crown flue above the reverberatory chamber, a series of vertical flues on either side of the muffle connecting the combustion chamber with the crown flue, a second series of vertical flues on either side of said muffle, and in the rear of said first named flues, connecting the crown flue with the reverberatory chamber, and a third series of vertical flues on either side of said muffle, and in the rear of said second named flues, connecting the reverberatory chamber with the crown flue in the rear of the baffle wall, said last named flues having a combined capacity less than that of the second named flues, whereby the products of combustion ascend from the combustion chamber to the crown flue, thence descend from the crown flue to the reverberatory chamber, and thence ascend from the reverberatory chamber to the crown flue in the rear of said baffle to escape to atmosphere.

5. A muffle leer comprising an outer furnace structure, an elevated muffle mounted therein, a longitudinal crown flue above the muffle, the side wall of the outer furnace being contracted in the rear of the muffle into alinement with the side walls of the latter to form a tunnel and the crown flue being extended beyond the rear end of said muffle and for a portion of the length of said tunnel, a combustion chamber under the forward portion of the muffle, a reverberatory chamber under the rear of said muffle, a vertical wall separating said chambers, a baffle wall intersecting the crown flue above said reverberatory chamber, a series of vertical flues of either side of the muffle connecting the combustion chamber with the crown flue, a second series of flues, in the rear of said first named flues, connecting the crown flue with the reverberatory chamber, a third series of flues, in the rear of said second named flues, connecting the reverberatory chamber with the crown flue in the rear of the baffle wall, and a stack connected to the rear end of said crown flue, whereby the products of combustion ascend from the combustion chamber 130

ber to the crown flue, thence descend from the crown flue to the reverberatory chamber, and thence ascend from the reverberatory chamber to the crown flue in the rear 5 of said baffle wall to escape through said stack.

6. A muffle leer comprising an outer furnace structure, an elevated muffle mounted therein, a longitudinal crown flue above the muffle, the side wall of the outer furnace being contracted in the rear of the muffle into alignment with the side walls of the latter to form a tunnel and the crown flue being extended beyond the rear end of said 15 muffle and for a portion of the length of said tunnel, a combustion chamber under the forward portion of the muffle, a reverberatory chamber under the rear end of said muffle, a vertical wall separating said 20 chambers, a baffle wall intersecting the crown flue above said reverberatory chamber, a series of vertical flues on either side of the muffle connecting the combustion chamber with the crown flue, a second series of flues, in the rear of said first named 25 flues, connecting the crown flues with the reverberatory chamber, a third series of flues, in the rear of said second named flues, connecting the reverberatory chamber with 30 the crown flue in the rear of the baffle wall, said last named flues having a less combined capacity than that of the second named flues, and a stack connected to the rear end of said crown flue, whereby the products of 35 combustion ascend from the combustion chamber to the crown flue, thence descend from the crown flue to the reverberatory chamber, and thence ascend from the reverberatory chamber to the crown flue in 40 the rear of said baffle wall to escape through said stack.

7. In a muffle leer construction, side wall tile for the muffle having front faces which fit together to form the muffle wall surface and rearwardly extending vertical edge flanges which contact with the outer side wall of the leer to form therewith vertical side flues.

8. In a muffle leer construction, side wall 50 tile for the muffle having front faces which fit together to form the muffle wall surface and rearwardly extending vertical edge flanges which contact with the outer side wall of the leer to form therewith vertical side flues, the abutting edges of said tile being tongued and grooved to form a tight joint.

9. In a muffle leer, a muffle roof structure composed of spaced apart arches provided 60 with laterally extending trough flanges and the intervening spaces being filled to complete the roof with roof tile having inwardly extending flanges along their opposed edges which flanges are seated in the trough flanges of the roof arches.

10. In a muffle leer, a muffle roof structure composed of spaced apart arches provided with laterally extending trough flanges, and the intervening spaces being filled to complete the roof with roof tile having inwardly 70 extending flanges along their opposed edges which flanges are seated in the trough flanges of the roof arches, the trough flanges of the roof arches being provided with a filling of plastic material to form a gas-tight joint. 75

11. In a muffle leer, a muffle roof structure composed of spaced apart arches provided with laterally extending trough flanges, and the intervening spaces being filled to complete the roof with roof tile having inwardly 80 extending flanges along their opposed edges which flanges are seated in the trough flanges of the roof arches, the abutting edges of said roof tile being provided with tongue and groove connection. 85

12. In a muffle leer, a muffle roof structure composed of spaced apart arches provided with laterally extending trough flanges, and the intervening spaces being filled to complete the roof with roof tile having inwardly 90 extending flanges along their opposed edges which flanges are seated in the trough flanges of the roof arches, the abutting edges of said roof tile being provided with tongue and groove connection, and the joints of said 95 structure being packed with plastic cement to render the same gas-tight.

13. A side wall tile for leer muffles provided with a plane face and two rearwardly extending vertical edge flanges, substantially 100 as and for the purpose set forth.

14. A side wall tile for leer muffles provided with a plane face and two rearwardly extending vertical edge flanges, the edges of 105 said tile being tongued and grooved for interlocking with each other, substantially as and for the purpose set forth.

15. A roof arch tile for leer muffles having laterally extending trough flanges to support the roof tile, the arch tile being longitudinally curved substantially as and for the 110 purpose set forth.

16. A roof arch tile for leer muffles having laterally extending trough flanges to support the roof tile, the arch tile being longitudinally curved and their ends being tongued and grooved to interlock with each other, substantially as and for the purpose set forth. 115

17. A roof tile for leer muffles curved to 120 fit the arch and having edge flanges to engage the roof arches, substantially as and for the purpose set forth.

18. A roof tile for leer muffles curved to 125 fit the arch and having edge flanges to engage the roof arches, the abutting ends of the roof tile being tongued and grooved to interlock together, substantially as and for the purpose set forth.

19. A floor structure for the muffle of a 130

muffle leer comprising wing walls extending inwardly from the side walls of the leer, piers between the ends of opposed wing walls, and flat floor tile supported on said wing walls and piers, substantially as and for the purpose set forth.

20. A floor structure for the muffle of a muffle leer comprising wing walls extending inwardly from the side walls of the leer,

piers between the ends of opposed wing walls, and flat floor tile supported on said wing walls and piers, the abutting edges of said floor tile being tongued and grooved to interlock together, substantially as and for the purpose set forth.

Signed at Pittsburgh, Pa., this 24th day of November, 1919.

PAUL L. GEER.
